UNITED STATES PATENT OFFICE.

JOHN E. CHALMAN, OF CHICAGO, ILLINOIS, ASSIGNOR TO UNION SPECIAL MACHINE COMPANY, OF CHICAGO, ILLINOIS, A CORPORATION OF ILLINOIS.

PRESSER-FOOT FOR SEWING-MACHINES.

1,300,928.

Specification of Letters Patent. Patented Apr. 15, 1919.

Application filed May 3, 1916. Serial No. 95,093.

To all whom it may concern:

Be it known that I, JOHN E. CHALMAN, a citizen of the United States, residing at Chicago, in the county of Cook, State of Illinois, have invented certain new and useful Improvements in Presser-Feet for Sewing-Machines, of which the following is a description, reference being had to the accompanying drawing, and to the figures of reference marked thereon.

The invention relates to new and useful improvements in a presser foot for sewing machines and more particularly to a presser foot of the character shown in the patent to Allan, No. 857,431, granted June 18th, 1907, which is especially adapted for tipping shoes.

An object of the invention is to provide means for supporting the guide whereby the same may be shifted laterally to predetermined guiding positions.

A further object of the invention is to provide a guide of the above character with means whereby the guide may be shifted on its support for varying the set positions of the guide relative to the needle or needles of the stitching mechanism.

These and other objects will in part be obvious and will in part be hereinafter more fully disclosed.

In the drawings, which show by way of illustration, one embodiment of the invention:—

Figure 1, is a view partly in front elevation and partly in section, showing a portion of a sewing machine having my improved presser foot applied thereto;

Fig. 2 is a perspective view of the presser foot detached from the machine;

Fig. 3 is a view partly in plan and partly in section of the same;

Fig. 4 is a vertical sectional view through the presser foot in line with one of the needle openings;

Fig. 5 is a vertical sectional view taken transversely through the presser foot;

Fig. 6 is a view, showing the presser foot in plan and showing a shoe tip being attached to the vamp, the guide being set for directing the tip so as to form the lines of stitching adjacent the edge of the tip;

Fig. 7 is a similar view showing the guide positioned for forming the lines of stitching at the outer side of the perforations in the tip;

Fig. 8 is a sectional view through a portion of a tip and a vamp, showing diagrammatically the position of the lines of stitching;

Fig. 9 is a view showing a portion of a vamp and a tip attached thereto; and

Fig. 10 is a bottom plan view of the presser foot.

It is well known that the tips of shoes are often ornamented by forming a series of openings therethrough adjacent the edge of the tip which is secured to the vamp. This edge is secured to the vamp by one or two lines of stitches which pass through the tip and the vamp on opposite sides of the series of openings. This is known in the art as a "tipping" operation.

In order that the finished shoe may have the proper appearance, it is essential that these lines of stitches should be disposed an equal distance from the outer edges of the perforations or openings in the tip.

The present invention has to do with the guide for guiding the tip so as to properly position the lines of stitches referred to. This guide is mounted on the support which is movable so as to shift the guide laterally relative to the needle and this support is held yieldingly in predetermined positions relative to the needles. The guide itself is adjustably attached to the support so that it may be adjusted relative to the set positions of the support. This permits the guide to be not only shifted but adjusted and a proper positioning of the tip for placing the lines of stitching relative to the perforations in the tip and also relative to the edge of the tip so that the finished article shall be properly constructed.

Referring more in detail to the drawings, I have shown my improved presser foot 1, as applied to a sewing machine having a needle bar 2 carrying two needles 3 and 4. There is a looper 5 which co-operates with the needle 3 and a looper 6 which co-operates with the needle 4. The needles and the loopers may be operated in any well known manner.

The presser foot 1 is carried by a presser bar 7. Said presser foot comprises a shank 8 which is clamped to the presser bar 7 and a foot section 9 is pivotally secured by a pivot rod 10 to the shank 8 so that said presser foot has a slight lateral rocking movement.

Mounted on the presser foot 9 is an edge 5 guide 11. Said edge guide 11 is fixed to a shank 12 which slides in a groove 13 in the presser foot 9. The edge guide is provided with a section 14 which extends underneath the presser foot and the inner edge 15 of this section 14 is the guide proper which engages the edge of the tip and directs the same to the needles. The edge guide 11 has 10 an upwardly extending forked standard 16. This standard is threaded to engage a threaded adjusting screw 17. The adjusting screw 17 is mounted in a support 18. The presser foot 9 has an upwardly extending member 19 which is provided with a transverse guide way adapted to receive the support 18. Said support 18 is formed with two notches 20 and 21. A yielding finger 22 carries a pin 23 which is adapted to engage either notch 20 or 21 and thus yieldingly hold the support in two different set positions. The shaping of the end of the pin and the recesses is such that a pressure endwise of the support will move said support in the guide way and shift the same from one set position to the other. On the end of the support 18 is a cap 24 which limits the movement of the support if it is moved beyond the point where the pin 23 20 engages the notch 21.

In Figs. 8 and 9 of the drawings, I have shown a shoe vamp indicated at V to which a tip is attached, indicated at T. This tip is provided with a row of openings or perforations p which extend in a direction parallel with the edge 25 of the tip T. I have also shown in these figures a tip secured to the vamp by two lines of stitching s located at one side of the openings or perforations 30 p and two lines of stitching s' located the other side of the openings or perforations p.

In the operation of my device the edge guide may be set as shown in Fig. 6, that is, with the pin 23 engaging the notch 20. 40 This is one set position for the support 18 and when so positioned the vamp indicated at V and the tip indicated at T in Fig. 6 may be guided to the presser foot so that the edge 25 of the tip T will be in engagement with the guiding edge 15 of my improved guide 11. This will position the lines of stitching s so that they will be between the perforations and the edge of the tip and, of course, parallel with the edge 50 of the tip.

After this line of stitching has been formed connecting the tip to the vamp, then the guide is shifted to the position shown in Fig. 7. This may be done by pressing on 60 the cap 24 which causes the pin 23 to rise out of the recess 20 and engage the recess 21. When thus positioned the line of stitching s' will be formed and this line of stitching will be parallel with the edge 25 of the tip 65 and located on the opposite sides of the per-

forations or openings p. The presser foot is provided with openings 26 and 27 and the opening 26 is for the needle 3 and the opening 27 for the needle 4.

It sometimes happens that the openings 70 or perforations in the tip of the shoe vary slightly in their distance from the edge of the tip. By turning the adjusting screw 17, the position of the guide relative to the support may be changed, and the guide may be 75 shifted from one predetermined set position to another predetermined set position relative to the needle openings. This will shift the guide laterally from one predetermined set position to another predetermined set 80 position. By turning the screw 17 the set positions of the guide may be varied although the set positions of the support 18 are fixed. Therefore, the distance between one set position and the other will remain 85 the same unless the screw 17 is turned and if the distance of the perforations or openings p from the edge of the tip be increased then by turning the screw 17 the set positions may be shifted back from the edge of 90 the tip so that the openings or perforations p will be centered between the lines of stitching.

It also sometimes happens that the openings or perforations will vary slightly in 95 size. Under these conditions the first line of stitching s may be placed between the perforations or openings p and the edge of the tip, then the guide shifted for positioning the tip for the line of stitching s' and the 100 screw 17 turned sufficiently so as to center the perforations or openings between the lines of stitching. This, in other words, shifts the set positions of the guide so that the distance between the same may be either 105 slightly greater or slightly less as desired although the distance between the set positions of the support 18 remains fixed.

It is obvious that minor changes in the details of construction may be made without departing from the spirit of the invention as set forth in the appended claims.

Having thus described my invention, what I claim as new and desire to secure by Letters Patent, is:—

1. A presser foot for sewing machines, comprising a foot section having a needle opening, an edge guide extending underneath the presser foot, means for supporting said edge guide whereby the same may 120 be shifted to different set positions and means for adjusting said set positions of the guide relative to the needle opening in the presser foot.

2. A presser foot for sewing machines, 125 comprising a foot section having a needle opening, an edge guide extending underneath the presser foot and shiftable laterally to different positions relative to the needle opening, a support for said edge 130

guide, means for holding the support in predetermined positions relative to the needle and means for adjusting the guide relative to the support for varying the set positions of the guide relative to the needle opening.

3. A presser foot for sewing machines comprising a foot section having a needle opening, an edge guide shiftable to different positions relative to the needle opening, 10 a support for said guide, means for yieldingly holding said support in predetermined positions relative to the needle opening and means for adjusting the guide relative to the support for varying the set positions 15 of the guide relative to the needle opening.

4. A presser foot for sewing machines comprising a foot section having a needle opening, an edge guide having a sliding connection with the foot section, a support mounted on the presser foot and adapted to slide laterally relative to the foot, a notch and coöperating pin for holding said support in predetermined positions and ad-

justable means for connecting the guide to the support whereby the same may be shifted with the support and adjusted relative to the support.

5. A presser foot for sewing machines comprising a foot section having a needle opening, an edge guide having a sliding connection with the foot section, a support mounted on the presser foot and adapted to slide laterally relative to the foot, said support having spaced notches therein, a yielding member for engaging said notches for holding the support in predetermined positions, an adjusting screw for connecting the support to the guide whereby the guide is shifted with the support and whereby said 40 guide may be adjusted relative to the support.

In testimony whereof, I affix my signature, in the presence of two witnesses.

JOHN E. CHALMAN.
